MALCOLM CURRY, OF SCARSDALE, NEW YORK, ASSIGNOR TO THE AMERICAN THREAD COMPANY, OF NEW YORK, N. Y., A CORPORATION OF NEW JERSEY.

THREAD PACKAGE.

Application filed July 30, 1925. Serial No. 46,975.

My invention relates to a new and improved thread package and has for its object to provide a package adapted for the putting up of thread, such as embroidery 5 cotton or embroidery silk, floss and the like. My invention is particularly applicable for embroidery materials. Heretofore such threads have usually been put up in skein form. When such materials are made into 10 skeins, the skein is ordinarily opened up and cut at one point so as to produce a number of equal thread lengths. These cut skeins are ordinarily put over the neck of the user and one length is removed at a time. When 15 a skein is so cut, it is impracticable to remove less than one length, if that is desired, without wasting the remainder of the length. Moreover, when a skein is so cut it is liable to become tangled or snarled, 20 particularly when the work is discontinued before the skein is entirely consumed. Moreover, the thread packages put up in skeins are liable to be affected by handling and moisture and to become soiled. My invention 25 has for its object to overcome each and all of these difficulties and also to provide a skein in which the goods are exposed for matching without being handled. It further has for its object to provide a package 30 which can be cheaply put up. It further has for its object to provide a package of little bulk which retains any applied trademark, color number, name, or advertising matter until it is used up. It further has 35 for its object to produce a package of pleasing appearance. It further has for its object to provide a package which can be cut in two or more sections for sales purposes, if desired. It further has for its object to 40 provide a package in which there is no waste in winding.

The following is a description of an embodiment of my invention, reference being had to the accompanying drawings, in 45 which,

Fig. 1 shows a side elevation of a package embodying my invention, part being shown broken away;

Fig. 2 shows the reverse side of a similar 50 package from which the thread has been partially unwound;

Fig. 3 shows a sectional view on the line 3—3, Fig. 1, somewhat enlarged;

Fig. 4 shows a sectional view on the line 4—4, Fig. 1, somewhat enlarged; and 55

Fig. 5 shows a transverse section of a modification.

Referring more particularly to the drawings, 2 is a core which is preferably made of a sheet of paper having overlapping portions, preferably gummed together, as at 4. This core is preferably in the form of a flat oval having rounded edges. 6 is a strand of thread wound thereon in a single layer so as to form a close helix. 8 is an envelope preferably in the form of a flattened oval, closely surrounding the helix and having overlapping portions secured together, as at 10. 12 is a tag which may bear the color number attached to the inner wall 65 of the tubular core and the outer wall of the tubular sheet, securing the same together at the opposite end from the unwinding end. The envelope may also be secured directly 70 to the core at this point. 14 is a label which 75 may bear the maker's name, trademark, advertising matter, etc., secured to the outer surface of the envelope.

The core 2 and envelope 8 are tubular members and are made of sheets having 80 their edges secured together. Preferably the outer edge of the sheet from which the core is formed and the inner edge of the sheet from which the envelope is formed 85 point in the same direction, and in the opposite direction to the direction of the unwinding end 16 of said helix so as not to catch the unwinding thread. For appearance and ease in manufacture the overlapping edges of the envelope are preferably 90 parallel to the axis of the package as shown in Fig. 2. The envelope is preferably made, partly or wholly, of thin practically colorless transparent material. This envelope 95 being transparent, clearly shows the color of the thread upon the core. Cellophane secured by adhesive, or thin sheet gelatin, may be used. Sheet gelatin is of such character that it becomes adhesive when moistened, so that no additional adhesive is necessary for 100 securing the outer flap thereto after wrapping about the thread helix.

In using this package, the unwinding end of the thread is drawn off to the desired extent, and after the thread is severed at or 105 near the end of the envelope the remainder

is held within the package so that there is no danger of its becoming snarled or tangled. Any desired length can be cut off. The thread is protected against handling and moisture and soiling. The color of the goods is visible for matching and matching can be accomplished without handling the thread. The package is cheaply put up. The package retains the trademark, color number, name and advertising matter until used up. The package is a pleasing looking package and can be cut into sections for sales purposes. There is no waste in the winding. The core, on account of its rounded edges, holds the thread so as to prevent the formation of angular kinks therein. The core is visible through the transparent envelope when the thread is partially unwound so that any trademark or advertising matter printed thereon is visible through the envelope when the thread is removed.

In order to reduce the cost, a section only of the envelope may be made of the transparent material as shown at 18 in Fig. 5, the remainder 20 being of paper and secured to the edges of the transparent section.

In making the package, I perform the cores for a plurality of packages in a continuous strip, then wind a helix long enough for a plurality of packages continuously on said strip, then form a continuous envelope about said helix, and then, after securing the overlapping edges of the envelope, sever the core, helix and envelope at intervals to produce packages of the desired length. I preferably wind the helices in close sections with a spaced wind between the sections at the points where the severing is to be done.

As will be evident to those skilled in the art, my invention permits of various modifications without departing from the spirit thereof or the scope of the appended claims.

What I claim is:

1. A thread package comprising a core, a close wound helix of thread thereon, the thread being of such length as to render it desirable to remove the same in successive sections, and an envelope closely surrounding said helix whereby said envelope permits unwinding of the helix and at the same time holds any unremoved sections of said helix from fortuitous unwinding.

2. A thread package comprising a core, a close wound helix of thread thereon, the thread being of such length as to render it desirable to remove the same in successive sections, and an envelope closely surrounding said helix whereby said envelope permits unwinding of the helix and at the same time

holds any unremoved section of said helix from fortuitous unwinding, said core being relatively flat and having rounded edges.

3. A thread package comprising a core, a close wound helix of thread thereon, the thread being of such length as to render it desirable to remove the same in successive sections, and an envelope closely surrounding said helix whereby said envelope permits unwinding of the helix and at the same time holds any unremoved section of said helix from fortuitous unwinding, said envelope being formed of a sheet having overlapping edges, the inner edge of the sheet forming the envelope pointing in the opposite direction to the direction of winding of the thread at one end of said helix, said core and envelope being secured together adjacent to the other end of said helix.

4. A thread package comprising a core, a close wound helix of thread thereon, the thread being of such length as to render it desirable to remove the same in successive sections, and an envelope closely surrounding said helix whereby said envelope permits unwinding of the helix and at the same time holds any unremoved section of said helix from fortuitous unwinding, said core being formed of a sheet having overlapping edges, the outer edge of the sheet forming the core pointing in the opposite direction to the direction of winding of the thread at one end of said helix, said core and envelope being secured together adjacent to the other end of said helix.

5. A thread package comprising a core, a close wound helix of thread thereon, the thread being of such length as to render it desirable to remove the same in successive sections, and an envelope closely surrounding said helix whereby said envelope permits unwinding of the helix and at the same time holds any unremoved section of said helix from fortuitous unwinding, said envelope being formed of a sheet having overlapping edges, the inner edge of the sheet forming the envelope pointing in the opposite direction to the direction of the winding of the thread at one end of said helix, said core and envelope being secured together adjacent to the other end of said helix, said core being formed of a sheet having overlapping edges, the outer end of the sheet forming the core and pointing in the same direction as the inner end of the sheet forming the envelope.

In testimony whereof, I have signed my name to this specification this twenty-ninth day of July, 1925.

MALCOLM CURRY.
